UNITED STATES PATENT OFFICE.

PHILIP T. DODGE, OF WASHINGTON, DISTRICT OF COLUMBIA, ASSIGNOR
TO MERGENTHALER LINOTYPE COMPANY, A CORPORATION OF NEW
YORK.

LINOTYPE-MACHINE.

SPECIFICATION forming part of Letters Patent No. 764,116, dated July 5, 1904.
Application filed March 10, 1904. Serial No. 197,507. (No model.)

To all whom it may concern:

Be it known that I, PHILIP T. DODGE, of Washington, District of Columbia, have invented a new and useful Improvement in Linotype-Machines, of which the following is a specification.

My invention has reference to the Mergenthaler linotype and kindred machines, wherein a printing-slug or linotype is cast in a slotted mold against a line of matrices temporarily closing the face of the same, the type-metal being delivered into the mold at the rear from the perforated or slotted mouth of the melting-pot, which acts directly against and serves to close the mold.

The object of my invention is to reduce the weight of the linotypes and the amount of metal contained therein by forming cavities in the base thereof; and to this end it consists in providing the mouth or throat of the pot through which the molten metal is delivered with one or more studs or projections adapted to enter the mold and serve the office of cores therein, the studs being of such form that they may be withdrawn from the mold and from the slug without disturbing the latter. These studs or cores may be of any sectional form and of any suitable length, provided only they are adapted to be readily withdrawn from the mold and the slug therein. The openings for the admission of metal may be through, between, or in one side of the cores, as preferred.

In the accompanying drawings, Figure 1 represents a vertical cross-section through the mold of a linotype-machine with the matrices and my improved pot-mouth in operative relation thereto. Figs. 2 and 3 are respectively a face view and a cross-section of a mouth-piece in accordance with my invention: Fig. 4 is a view illustrating the same in an alternative or equivalent form. Figs. 5 and 6 are perspective views illustrating linotypes produced by my improved mechanism.

Referring to Figs. 1, 2, and 3, A represents a slotted mold wherein the linotype B is cast. This mold may be of any ordinary or suitable form and construction.

C represents the matrices alined tempora-

rily against the face of the mold in order that their cavities or matrices proper may form the corresponding characters in relief on the edge of the linotype.

D represents the delivery mouth or throat through which the molten metal is delivered into the mold from a melting-pot or other source of supply. This delivery-throat may be integral with the pot, as in the ordinary Mergenthaler machine, or it may be independently movable, as in other machines, the only requirement being that it shall connect with a supply of molten metal and means for delivering the same under suitable pressure into the mold.

The mold and the delivery-mouth will be movable one in relation to the other, as usual in this class of machines, so that the mouth may be seated against the base of the mold to close the same during the casting operation and the parts thereafter separated to permit the ejection of the linotype. Up to this point the parts may be constructed and arranged to operate in the ordinary manner.

In carrying my invention into effect I form on or apply to the mouth D in any suitable manner one or more projections or cores E, adapted to extend into the mold from the rear without closing or filling the same, so that when the linotype is cast these cores will produce cavities of like form in its base. They may be varied in length and in sectional form at will, provided only they leave at the base of the slug a sufficient body of metal to give it the requisite stability when in use.

In the form shown in Figs. 1, 2, and 3 the mouthpiece, adapted to produce a slug such as shown in Fig. 5, is of a dovetail form in cross-section and is driven endwise tightly into a corresponding groove in the pot-mouth, as is usual in linotype-machines. The cores or studs shown in Figs. 1, 2, and 3 are separated from each other lengthwise of the mouthpiece in order that the slug or linotype may be solid from one side to the other between the cavities, as shown in Fig. 5.

The holes F, through which the molten metal is delivered, may be located between the cores or projections or extended through the

cores, or both. The cores may be located so as to lie either at the top or the bottom of the mold-cavity in order to produce in the slug open cavities in one side or face, as shown 5 in Fig. 6.

It will be understood by the skilled mechanician that the studs may be made integral with the mouthpiece or separately formed and secured thereto in any suitable manner. As 10 it is a common practice to use a mouthpiece of maximum length in connection with a mold which is variable in length in order to cast linotypes of different lengths, the separately-formed studs or cores may be screwed into 15 the mouthpiece or otherwise attached in order that one or more of them may be removed when the mold is shortened in length.

In Fig. 3 I have shown the cores as screwed into the body of the mouthpiece that they may 20 be readily removed.

It will be observed that in my mechanism the mouthpiece of the pot acts directly against and serves to close the rear face of the mold and to form a surface on the rear edge of the 25 slug and that the projections formed in this mouthpiece are adapted to enter the mold and to be withdrawn endwise therefrom and from the slug therein. No sprue-plate, breaker, or other part is employed between the mold and 30 the pot. The slug is left undisturbed in the mold, so that it may be trimmed to the exact

height required in the usual manner by a knife acting across the face of the mold.

Having described my invention, what I claim is—

1. In a linotype-machine, a slotted mold in combination with a melting-pot having its delivery-mouth adapted to act directly against and close the base of the mold, and provided with one or more studs adapted to enter the 40 mold and to be withdrawn from the mold and from the slug therein.

2. As a new article of manufacture, a mouthpiece for a linotype-machine, adapted to fit directly against and close the rear face of the 45 mold, and provided with perforations for the passage of the metal, and with one or more studs adapted to enter the mold and to be withdrawn therefrom and from the slug 50 therein.

3. In a linotype-machine, a mouthpiece adapted to close the rear face of the mold, provided with studs adapted to enter the mold and to be withdrawn endwise therefrom and from the slug therein.

In testimony whereof I hereunto set my hand, this 5th day of February, 1904, in the presence of two attesting witnesses.

PHILIP T. DODGE.
